UNITED STATES PATENT OFFICE.

WILLIAM P. FEENEY, OF CHEBOYGAN, MICHIGAN.

FELT CONDITIONER FOR PAPER MACHINES.

Application filed March 3, 1926. Serial No. 91,816.

The present invention relates generally to paper making machines and the like and more particularly to a felt conditioner for restoring automatically the felts, which have been used therein as carriers, to their original condition.

In making paper, it is customary to have one or more endless belts or carriers usually made of felt or other fibrous material. The pulp from which the paper is made is placed in a large vat, and a cylindrical roller is placed in contact with the pulp liquid and rotated with its surface in engagement with the felt carrier to transfer a thin sheet of the pulp to the carrier. The pulp is then conveyed over a series of rollers and particularly one or more pressing rollers which apply a very substantial pressure to the pulp to remove the liquid therefrom, which is absorbed by the felt. The thin layer of pulp is then removed from the carrier which returns to receive a fresh layer. The felt, in passing through the various pressure rollers, becomes compressed and the fibers matted together, so that dust and particles of foreign matter adhere to and close up the interstices of the felt and it fails to perform its usual functions. In the old types of machines, this necessitated removing the felt about every twenty-four hours, to subject it to various cleaning operations which damaged the felt, and shortened its life to a marked degree. Rollers with needle points projecting from the surface thereof have been used as perforating devices to render the felt porous, but these naturally damage it and decrease its serviceability without materially restoring its original absorbing qualities.

The present construction is an improvement upon the invention shown in my Patent No. 1,567,584 dated December 29th, 1925, and contemplates working the felt automatically to separate the fibres and bring them back to their original shape or condition without removing the felt from the machine, and at the same time, to spray water thereon for removing any particles of dust or other material clogging the interstices of the felt and to remove the water and foreign matter from the felt by subjecting its surface to a vacuum. In this manner, the felt is automatically reconditioned, and washed during the operation of the machine and shutdowns are reduced to a minimum. The serviceability of the felt is greatly increased due

to the fact that it is not subjected to any destructive cleaning operations but the fibres are gently separated and restored to their original condition.

An object of the present invention is to recondition the felt used in paper machines and the like by subjecting it to a roller having a series of dome-like projections which distort and separate the fibers of the felt and bring them back to their original condition; to spray the felt with liquid adjacent the roller for removing foreign matter therefrom; and to subject the felt to a vacuum for removing the liquid and other matter.

Other and further objects of the invention will be obvious upon an understanding of the illustrated embodiment about to be described, or will be indicated in the appended claims, and many advantages other than those herein specifically referred to will occur to one skilled in the art upon employment of the invention in practice.

A preferred embodiment of the invention has been chosen for the purpose of illustration and description, and is shown in the accompanying drawings, wherein

Fig. 1 is a sectional view taken transversely of the felt along the line 1-1 of Fig. 3;

Fig. 2 is a sectional view through the rolling and spraying mechanism taken along the line 2-2 of Fig. 1;

Fig. 3 is a sectional view taken along the line 3-3 of Fig. 1 showing the path of the felt;

Fig. 4 is a detailed view of the felt conditioning roller with certain parts broken away to show the mounting thereof; and

Fig. 5 is a sectional view showing features of the suction mechanism.

In the present description, while the various parts of the paper making machine are not shown, it will be understood that the belt 10 extending over the rollers 11, 12, 13, 14, 15 and 16, is a portion of an endless belt of felt or the like which contacts with a roller partially immersed in a pulp liquid to receive a coating thereof, which is carried on the felt through one or more pressure rollers and then removed. The present invention is shown applied to the felt on its return to receive another coating of pulp and may for convenience be mounted on the framework of the machine.

At some suitable point in the path of the belt such as between the rollers 12 and 13,

a roller 20 is provided having a series of apertures 21 therein adapted to receive the threaded shanks 22 of the dome-like projections 24 mounted on the surface of the roller 20 to engage the felt and work the fibers therein back to their original condition. The apertures in the roller are formed in longitudinal rows on the surface thereof and preferably staggered so that the edges of the 10 projections in one row will be adjacent the centers of the projections in an adjacent row. In this manner the projections are lapped so that there will be no streaking of the felt.

To mount and properly support the roller 15 20 transversely of the felt, there is provided on the channel member 17 of the framework of the machine, a shaft 26 mounted in brackets 27 bolted to the member 17. Keyed to the shaft are a pair of arms 28 having inwardly extending barrels 29 on their free ends, into which suitable ball-bearings 30 are mounted and retained in position by means of the plugs 31, threaded into the ends of the barrels. The shaft 32 of the 25 roller 20 is carried by the ball-bearings 30 to permit free rotation thereof.

The roller 20 may be properly adjusted against the felt 10 or raised to its ineffective position by means of the lever 37 keyed to 30 shaft 26 and may be held in the desired position by the ratchet 34 keyed to shaft 26 and pawl 35 mounted on the bracket 36.

In some instances, it is desirable to cleanse the felt and to remove any foreign matter 35 which may adhere thereto, and for this purpose there is provided a pair of supporting members 38 attached to the arms 28 and adapted to receive at their upper portions the tube 39 plugged at one end as shown at 40, and having a row of apertures adapted to accommodate a series of nozzles 42 for supplying liquid thereto. An adjustable clamp 44 held in position by the wing nut 45 may be utilized for permitting rotation 45 of the tube 39 for adjustment of the nozzles with respect to the roller 20 and for directing the liquid as desired. A hose 47 is suitably attached to the open end of the tube 39 for supplying liquid, preferably water, to 50 the nozzles.

The surface of the felt to which the liquid is applied preferably is subjected to a suction device 48, which may comprise a tube 49 rotatably mounted in brackets 50 with a 55 second tube 51 mounted above it and connected with it by a pair of conduits 52 which are welded to each of the tubes to hold them in their proper position with respect to each other. The upper part of the tube 51 has a 60 slot 54 whose length is slightly less than the width of the felt so that it will be completely covered when the felt passes over it. The width of the slot is sufficiently narrow to produce a very strong current of air through 65 the felt with a pump of normal capacity.

A narrow slot has the advantage that the suction is greater with a pump of normal capacity and will draw the felt into the slot, thereby distorting and enlarging the interstices on the lower side thereof to facilitate 70 removal of foreign matter by the current of air passing therethrough. In this manner the water and foreign matter are removed from the felt and the felt is rendered more porous by the additional stretching and 75 slackening of the fibres therein.

The slot 54 may be moved into effective and ineffective positions with respect to the felt, by means of the lever 58. A slot 56 in one of the brackets 50, accommodates a projection 57 on the tube 49 to control the extreme positions of the mechanism as shown in solid and broken lines in Fig. 5. A suitable vacuum pump 60 may be connected through the pipe 61 to the open end of the 80 tube 49 for supplying the necessary suction.

In the operation of the device, the pawl 35 is raised and the lever 37 adjusted to apply the necessary pressure to the felt 10 to cause the projections 24 to press upon the felt to stretch and slacken the fibers therein, and to permit them to assume their original condition. The projections 24 are sufficiently large in curvature to distort the portions of the felt slightly without damage, thereby separating the fibres and increasing the absorbing power of the felt. The nozzles 42 may be adjusted and water applied to the roller and the felt to wash away any foreign matter such as dust and the like, adhering to the felt. If it is desired to use the roller without spraying the felt, the water supply may be turned off and the roller 20 alone used with or without the suction mechanism. When the spraying devices are utilized, the suction mechanism 48 is raised to its upright position by means of the lever 58 to apply sufficient suction to remove the liquid and foreign matter from the felt.

It will be seen that the above invention effectively restores the felt used in paper making machines to its original condition without removal thereof and without interfering in any way with the operation of the paper making machine. The dome-like projections on the roller separate the fibres of the felt without damaging it and facilitate the removal of foreign matter by the water sprayed thereon and by the suction mechanism. The long narrow slot in the latter 120 permits a pump of normal capacity to draw a strong current of air through the felt forcing it into the slot and forming a long narrow trough therein, thereby enlarging the interstices on the lower side of the felt so that the current of air will remove the foreign matter therefrom. The roller for working the felt, the spraying devices, or the suction mechanism may be applied to the felt independently, or in conjunction with the 125 130

other mechanisms, and independent adjusting mechanisms permit the adjustment of any one of the devices without interfering with the others.

5 As various changes may be made in the above embodiment without departing from the spirit of the invention, all matter herein set forth is to be interpreted as illustrative and not in a limiting sense.

10 Having thus described my invention, I claim:

1. A felt conditioner for paper machines and the like, comprising means having a metallic surface with a plurality of threaded 15 apertures therein and metallic dome-like projections with threaded shanks adapted to be secured in said apertures to engage and press upon the felt.

2. A felt conditioner for paper machines 20 and the like, comprising means having dome-like projections adapted to engage and distort said felt, and devices for spraying a liquid on said means.

3. A felt conditioner for paper machines 25 and the like, comprising a cylindrical roller extending transversely of the felt having dome-like projections on the surface thereof to engage and separate the fibers of said felt, and means for supplying liquid to said roller 30 to facilitate the restoration of the felt to its natural condition.

4. A felt conditioner for paper machines and the like, comprising a cylindrical roller 35 extending transversely of the felt and having dome-like projections on the surface thereof adapted to engage and reshape the fibers of said felt, and means adjustable with respect to the roller for spraying liquid to facilitate the restoration of the felt to its 40 original condition.

5. A felt conditioner for paper machines and the like, comprising a roller extending transversely of said felt, a pair of arms attached to the ends of said roller for supporting 45 it in proper position, spraying devices mounted on said arms adjustable with respect to said roller for supplying liquid to said felt adjacent said roller.

6. A felt conditioner for paper machines 50 and the like, comprising a roller extending transversely of said felt, a pair of arms attached to the ends of said roller for supporting it in proper position, spraying devices mounted on said arms adjustable with 55 respect to said roller for supplying liquid to said felt adjacent said roller, and means

for adjusting said arms to regulate the pressure applied to said felt by said roller.

7. A felt conditioner for paper machines and the like, comprising a roller adapted to 60 engage and press upon the felt, spraying devices adjustable with respect to said roller for spraying liquid on said roller, and means for regulating the pressure applied to the felt by said roller without disturbing the 65 relation of said spraying devices to said roller.

8. A felt conditioner for paper machines and the like, comprising a roller extending 70 transversely of the felt, spraying devices adjustable with respect to said roller to supply liquid thereto, and means for subjecting the surface of said felt to a vacuum for removing the liquid therefrom.

9. A felt conditioner for paper machines 75 and the like, comprising a roller, means for supporting said roller transversely of said felt, spraying devices mounted on said means and adjustable with respect to said roller for supplying liquid to said felt, and 80 mechanism for subjecting the surface of said felt to a vacuum, means for rendering said roller and said vacuum ineffective.

10. A felt conditioner for paper machines and the like, comprising means having dome-like projections for engaging and pressing said felt, a pair of arms for supporting said means transversely of said felt, spraying devices mounted on said arms and adjustable with respect to said means, mechanism 85 for subjecting said felt to a vacuum, and levers for removing said means and said mechanism into ineffective positions.

11. A felt conditioner for paper machines and the like, comprising a pair of tubes 95 mounted one above the other, a conduit interconnecting said tubes, one of said tubes having a narrow slot extending longitudinally thereof to be effective upon felt passed over said slot.

12. A felt conditioner for paper machines and the like, comprising a tube rotatably mounted, a second tube mounted to rotate about the axis of said first tube, a conduit connecting said tubes, means connected to said first tube for producing a vacuum therein, said second tube having a narrow slot extending longitudinally thereof to be effective upon felt passed thereover, and means for rotating said second tube into effective 105 and ineffective positions.

WILLIAM P. FEENEY.
